(57) CLAIM

The ornamental design for a handbag, as shown and described.

DESCRIPTION

The patent or application file contains at least one drawing executed in color. Copies of this patent or patent application publication with color drawing(s) will be provided by the Office upon request and payment of the necessary fee.

FIG. 1 is a front left perspective view of a handbag showing my new design;

FIG. 2 is a front elevation view thereof;

FIG. 3 is a rear elevation view thereof;

FIG. 4 is a left side view thereof;

FIG. 5 is a right side view thereof;

FIG. 6 is a top front perspective view thereof;

FIG. 7 is a top plan view thereof in an alternate configuration for use, where the top handles are rotated downward and toward the front and rear sides; and,

FIG. 8 is a bottom view thereof in an alternate configuration for use, where the top handles are rotated to extend perpendicular past the front and rear sides.
